UNITED STATES PATENT OFFICE.

CHARLES G. HORNUNG, OF BUFFALO, NEW YORK, ASSIGNOR TO LARKIN CO., OF BUFFALO, NEW YORK.

HOLDER FOR SEMISOLID MATERIALS.

1,391,253.

Specification of Letters Patent. Patented Sept. 20, 1921.

Application filed January 9, 1920. Serial No. 350,267.

To all whom it may concern:

Be it known that I, CHARLES G. HORNUNG, a citizen of the United States, residing at Buffalo, in the county of Erie and State of 5 New York, have invented a new and useful Improvement in Holders for Semisolid Materials, of which the following is a specification.

This invention relates to holders or containers for semi-solid substances or material, such as shaving soap, polishes or toilet preparations, which are so constructed that the contents may be advanced or fed toward or through the open end of the holder.

10 The objects of the invention are to provide a holder or container of this kind with means of improved construction for frictionally holding the contents in the desired relation to the open end of the holder; also 15 to provide means of this kind of improved construction which are adapted to both grip the contents and to frictionally engage the sides of the holder so as to hold the substance in any desired position in the holder; 20 also to provide a holder of this kind which is so constructed that the parts thereof, together with the contents may easily be assembled; also to improve devices of this kind 25 in other respects hereinafter specified.

30 In the accompanying drawings:

Figure 1 is an elevation of the holder embodying the invention showing the contents extending beyond the upper end thereof.

Fig. 2 is a sectional elevation thereof, 35 with a cap or closure on the upper end of the holder.

Fig. 3 is a fragmentary sectional elevation thereof, on an enlarged scale.

Fig. 4 is a sectional elevation thereof, 40 showing the parts of the holder and the contents in position to be assembled.

Fig. 5 is a top plan view of the gripping device.

Fig. 6 is a plan view of a spring ring, 45 which may be used in connection with the gripping device.

A represents the body portion of the holder which is preferably in the form of a cylindrical housing having an opening *a* 50 at its lower end, and B represents the semisolid substance forming the contents of the holder which may be a stick of shaving soap, polish, or any other material and which is preferably so formed as to fit loosely into 55 the interior of the body portion A of the

holder. The stick of material is frictionally held in the holder so that it can be advanced toward the open end of the holder by pushing the substance lengthwise of the holder by means of a finger or implement 60 inserted through the hole *a* of the holder.

The device for frictionally holding the stick of material in the holder preferably includes a frictional slide and gripping member C which in the construction shown 65 has a substantially flat bottom portion *c* and an upwardly extending annular flange portion *c'* adapted to surround the lower end of the stick of material. The flange or portion *c'* is provided with slits *c*² which 70 divide the flange of the gripping member into a plurality of gripping fingers *c*³. The upper portions of the fingers are preferably provided with beads or outwardly curved portions *c*⁴ which are adapted when the 75 device is in operative position in the holder to engage the inner face of the body portion of the holder. The upper extremities of the gripping fingers extend inwardly and form projections *c*⁵ which are adapted to extend 80 into the stick or substance B. The fingers *c*³ are formed to normally extend outwardly as shown in Fig. 4 and when the parts of the holder and the stick are assembled, the lower end of the stick is placed into the bot- 85 tom portion of the gripping member and the stick and gripping member together are then forced into the upper end of the body portion A of the holder. This moves the fingers *c*³ inwardly and causes the projections *c*⁵ thereof to enter into the stick of material 90 and the beaded portions *c*⁴ to yieldingly press against the inner face of the body portion A of the holder.

The gripping fingers *c*³ may either be 95 made of resilient material so that they will yieldingly press against the wall of the container, due to their own resiliency, or if desired, an expanding ring D may be employed which can be placed into the annular groove formed by the beads *c*⁴ of the fingers and thus press the fingers outwardly. This ring is preferably made of spring material and when the stick of material is placed into the container, the ring will be 100 pressed into the stick of material and the engagement of the ring with the stick and with the fingers forms a connection between these two parts which securely holds the stick to the gripping member. The ring 105 110

will press the fingers c^3 against the inner sides of the wall of the container and yieldingly hold the stick of material in any position in which it is set.

- 5 In order to facilitate the insertion of the gripping member and stick of material in the body portion A of the holder, the upper edge of the holder is preferably provided with an outwardly curled bead E which
 10 strengthens the upper portion of the container and also guides the gripping member into the container. This bead has the further purpose of preventing the outer edge of the container from injuring the surface
 15 upon which the material in the container is to be applied; for example, if the container is used for shaving soap, the bead E will prevent a person using the soap from injuring his face on the upper edge of the
 20 container.

F represents a cap or closure for the container which may be of any usual or desired form, that shown being provided with a reduced portion f which enters into the
 25 upper edge of the holder.

By means of the construction described, the stick of material may be moved relatively to the container as desired and will be yieldingly held in any desired position.
 30 A person using the holder need not touch the stick of material when using the same. The holder may be repeatedly used since the gripping member can be easily removed from the container and a new stick of material inserted.

I claim as my invention:

1. A container for a stick of material comprising a tubular housing having an open end, and a finger opening in its other
 40 end, a dished member adapted to slide in said housing, said dished member comprising a base upon which an end of said stick is adapted to rest and upwardly extending fingers on said base arranged at the sides
 45 of said stick, and a resilient member bearing on said stick and engaging said fingers for yieldingly pressing said fingers into gripping engagement with said housing.

2. A container for a stick of material
 50 comprising a tubular housing having an open end, and a finger opening in its other end, a dished member adapted to slide in

said housing, said dished member comprising a base upon which an end of said stick is adapted to rest and upwardly extending 55 fingers on said base arranged at the sides of said stick, said fingers having outwardly bent portions frictionally engaging said housing and forming on their inner faces a substantially annular groove and a ring of 60 resilient material arranged in said groove and bearing on said stick and pressing said fingers outwardly into gripping engagement with said housing.

3. A container for a stick of material 65 comprising a tubular housing having an open end, and a finger opening in its other end, a dished member adapted to slide in said housing, said dished member comprising a base upon which an end of said stick 70 is adapted to rest and upwardly extending fingers on said base arranged at the sides of said stick, said fingers having outwardly and inwardly bent upper end portions frictionally engaging said housing and projecting 75 into said stick and forming on their inner faces a substantially annular groove, and a ring of resilient material arranged in said groove and pressing the outwardly bent 80 portions of said fingers into gripping engagement with said housing.

4. A container for a stick of material, comprising a tubular housing having an open end, and a finger opening at its other end, a stick-holding member adapted to 85 slide in said housing and comprising a flat base portion on which an end of the stick is adapted to rest and projecting finger portions adapted to embrace the sides of said stick adjacent said end, said finger portions 90 having outwardly and inwardly bent upper ends frictionally engaging said housing and projecting into said stick, and a resilient ring surrounding said stick and bearing upon the upper ends of said finger portions 95 and pressing said outwardly bent portions into gripping engagement with said housing.

Witness my hand this 7th day of January, 1920.

CHARLES G. HORNUNG.
